UNITED STATES PATENT OFFICE.

JACOB J. PLUCKER, OF PHILADELPHIA, PENNSYLVANIA, ASSIGNOR TO
CATHERINE A. PLUCKER AND HOWARD W. PLUCKER.

SHUTTER.

SPECIFICATION forming part of Letters Patent No. 734,607, dated July 28, 1903.

Original application filed February 11, 1903, Serial No. 142,884. Divided and this application filed April 4, 1903. Serial No. 151,080. (No model.)

To all whom it may concern:

Be it known that I, JACOB J. PLUCKER, a citizen of the United States of America, and a resident of 6820 Paschall avenue, Philadelphia, Pennsylvania, have invented certain new and useful Improvements in Shutters, of which the following is a specification.

My invention relates to certain new and useful improvements in shutters, and this application is a division of my application Serial No. 142,884, filed February 11, 1903; and the particular object thereof is to form a shutter from sheet metal which shall be strong and durable and at the same time cheap to manufacture.

With these objects in view my invention consists in certain parts and combinations, the preferred form of which will be first described and then the invention pointed out in the claims.

Referring to the drawings, certain like numerals are used to designate the parts.

Figure 1 is a perspective view of a shutter embodying my invention. Fig. 2 is a longitudinal section of the same. Fig. 3 is a transverse section.

1 designates a blank of metal or similar material, and, as preferably shown, its edges are bent at 2 in opposite directions, so that 30 when the shutters are mounted they will cooperate with each other and close more tightly.

Longitudinally of the blank 2 is formed a V-shaped depression 3, forming a rib which 35 is parallel to the axis of the shutter, the groove extending clear to the ends of the blank. The blank at each end is cut into the sides of the longitudinal groove, and then the sides of the blank outside of this groove are bent 40 up to form stems 4, which are preferably and as shown square in cross-section, and these

stems form the pivotal portions of the shutter. Preferably and as shown the longitudinal groove not only serves to stiffen and strengthen the shutters, but also forms two 45 sides of the stem, as is best shown in Fig. 3. By having the groove form two sides of the stem it is very easy to bend the other two sides of the stem, which are formed by cutting the blank into the outer sides of the 50 groove, as it is merely necessary to bend them over the former until they meet.

Having thus described my invention, what I claim as new, and desire to secure by Letters Patent, is—

1. As a new article of manufacture, a sheet-metal shutter provided with a rib parallel to the axis of rotation of the shutter, the shutter at each end being formed with a pivotal stem integral with the shutter and of which 60 the rib forms a part.

2. As a new article of manufacture, a sheet-metal shutter provided with a rib parallel to the axis of rotation of the shutter, the shutter at each end being formed with a pivotal 65 stem square in cross-section and integral with the shutter and of which the rib forms a part.

3. As a new article of manufacture, a sheet-metal shutter provided with a V-shaped 70 groove parallel to the axis of rotation of the shutter, the shutter at each end being formed with a pivotal stem square in cross-section, integral with the shutter and of which the rib forms a part.

Signed by me at Philadelphia, Pennsylvania, this 1st day of April, 1903.

JACOB J. PLUCKER.
